UNITED STATES PATENT OFFICE.

HENRY GELNER, OF GARNER, IOWA.

BRIDGE.

1,253,809.

Specification of Letters Patent. Patented Jan. 15, 1918.

Application filed March 13, 1917. Serial No. 154,501.

To all whom it may concern:

Be it known that I, HENRY GELNER, a citizen of the United States, residing at Garner, in the county of Hancock and State 5 of Iowa, have invented certain new and useful Improvements in Bridges; and I do hereby declare the following to be a full, clear, and exact description of the invention, such as will enable others skilled in 10 the art to which it appertains to make and use the same.

The invention relates to improvements in bridges.

The object of the present invention is to 15 improve the construction of bridges and to provide a simple, practical and efficient bridge of strong, durable and comparatively inexpensive construction, which will be self-supporting and in which the means for sup- 20 porting the bridge intermediate of the ends thereof will be in proportion to the weight to which the bridge is subjected.

With these and other objects in view, the invention consists in the construction and 25 novel combination of parts hereinafter fully described, illustrated in the accompanying drawing and pointed out in the claims here-to appended; it being understood that various changes in the form, proportion, size 30 and minor details of construction, within the scope of the claims, may be resorted to without departing from the spirit or sacrificing any of the advantages of the invention.

35 In the drawing:

Figure 1 is a side elevation of a bridge constructed in accordance with this invention.

Fig. 2 is a horizontal sectional view on the 40 line 2—2 of Fig. 1.

Fig. 3 is a detail sectional view illustrating the manner of mounting the ends of the truss of the bridge.

Like numerals of reference designate cor- 45 responding parts in the several figures of the drawing.

In the accompanying drawing, in which is illustrated the preferred embodiment of the invention, the bridge comprises in its con- 50 struction a truss composed of a horizontal top member 1, inclined end members 2, a central vertical strut member 3 and a horizontal connecting beam or member 4 sup- 55 porting the strut member and the flooring 5 of the bridge and suitably secured at its ends to the inclined end members 2 at points ad-

jacent to the lower ends thereof, but spaced from the same to provide projecting lower arms or portions 6, which extend below the connecting beam 4 and the floor 5 of the 60 bridge. The inclined end members 2 are suitably secured at their opposite terminals to the top member 1, which is braced adjacent to its ends by inclined braces 7 extending across the angles formed by the inclined 65 end members and the top connecting member. The truss constitutes the main framework of the bridge and it may be varied in dimensions to provide a bridge of the desired size and may be internally braced to 70 secure the requisite strength of the framework which may be constructed of any suitable material, either wood or metal or a combination of both.

The bridge is supported by inclined levers 75 8 consisting of longitudinally disposed beams extending from the end portions of the truss inwardly and terminating short of the center thereof and fulcrumed adjacent their outer ends on piers 9 of concrete 80 or other suitable material. The piers 9, which are tapered or approximately triangular in end elevation, may be conveniently located at opposite sides of a stream or other place to be bridged, and the levers 8, which 85 are located at opposite sides of the bridge, extend inwardly and outwardly from the apexes of the transverse piers 9 and have relatively short outer arms and relatively long inner arms. The outer arms receive 90 the depending lower terminal portions of the inclined members 2 which rest upon the outer arms adjacent to the apexes of the piers, and the inner arms 8, which extend to the central portion of the sides of the bridge. 95 The levers may be secured to the frame of the bridge by yokes 10 or other suitable fastening means, and the beams, which constitute the levers, may be provided with sockets or seats 11 in their upper faces to receive 100 the lower ends 12 of the inclined end members of the truss of the bridge to form a fulcrum or bearing of the same if desired. The remaining weight of the truss rests upon the outer arms of the inclined levers and the 105 latter may be proportioned to produce the desired pressure on the under side of the lower connecting beams 5, which may be equipped with wear plates 13 to receive the upper ends of the inner arms of the inclined 110 levers. The inclined levers render the bridge self-supporting, and the sustaining pressure

at the center of the bridge will increase with the weight to which the bridge is subjected.

In practice the bridge will be suitably anchored and the approaches to the bridge will be built up substantially flush with the floor. As this is well understood in the construction of bridges of this type, illustration thereof is deemed unnecessary.

What is claimed is:

- 10 1. A bridge of the class described including a truss having downwardly extending arms or portions at the ends, and inclined longitudinally disposed supporting levers fulcrumed intermediate of their ends to form inner and outer arms, the outer arms receiving and supporting the depending arms or portions of the truss and the inner arms of the levers extending beneath and sustaining the weight of the bridge at the center thereof.
- 20 2. A bridge of the class described including a truss constituting the frame work of the bridge and having downwardly projecting terminal portions or arms, piers forming fulcrums, and longitudinally disposed inclined levers fulcrumed intermediate of their ends on the piers to form relatively short outer arms and relatively long inner arms, the outer arms receiving the depend-

ing arms or portions of the ends of the truss and the inner arms extending beneath the truss and supporting the bridge at opposite sides of the center of the same.

3. A bridge of the class described including spaced tapered piers forming fulcrums, inclined levers supported upon the piers and extending inwardly and outwardly therefrom to provide relatively long inner arms and relatively short outer arms, and a truss composed of inclined end members having depending terminal portions supported upon the outer arms of the inclined levers, an upper connecting member secured at its ends to the upper terminals of the end members, a lower horizontal connecting and supporting member secured at its terminals to the inclined end members and supported intermediate of its ends at opposite sides of its center by the inner arms of the levers, and a strut interposed between the upper and lower connecting members.

In testimony whereof I affix my signature in presence of two witnesses.

HENRY GELNER.
